UNITED STATES PATENT OFFICE.

EDDY M. KLINTBERG, OF SEATTLE, WASHINGTON.

EXTINGUISHER FOR BURNERS.

1,104,905.

Specification of Letters Patent. Patented July 28, 1914.

Application filed January 3, 1914. Serial No. 810,194.

To all whom it may concern:

Be it known that I, EDDY M. KLINTBERG, a citizen of the United States of America, and a resident of the city of Seattle, in the county of King and State of Washington, have invented certain new and useful Improvements in Extinguishers for Burners, of which the following is a specification.

The present invention relates to a device of the above character and more particularly to extinguishers for liquid fuel burners, and it has for its primary aim to provide such a device which will operate efficiently to extinguish the flame.

Other objects in view are the provision of a mechanism for operating the extinguisher after an interval of time subsequent to the starting of the aforesaid mechanism, and a signal means operable at a predetermined period anterior to the act of extinguishment.

Further objects will appear as the description progresses and those features of construction, combinations and arrangements of parts on which I desire protection succinctly defined in the appended claims.

For a full understanding of the invention, reference is to be had to the following specification and the accompanying drawings wherein like characters of reference denote like parts throughout.

Figure 1 is a horizontal section taken on line 1—1 of Fig. 2, showing my invention applied; Fig. 2 is a vertical section on line 2—2 of Fig. 1; Fig. 3 is a horizontal sectional view taken on line 3—3 of Fig. 4 disclosing the extinguisher operating mechanism; Fig. 4 is a vertical section of the device taken at right angles to point of view 40 of Fig. 2; and Figs. 5 and 6 are perspectives of the extinguishing cap and rocker member, respectively.

The burner, to which my invention is applied, is preferably of the ordinary type of kerosene burner consisting of the base 1 having the depending threaded portion 2 for mounting the burner on a font, and the burner cap 3 preferably hinged to the base, as at 4, and formed with a flame aperture 5 disposed in alignment with the wick tube 6, which latter, with the usual air tube 7, is carried by and passes through the base 1.

The extinguisher consists of a plate 8 having its ends downturned and terminating in reduced trunnions 9 which are preferably journaled in the cap 3 for swinging the plate

over and from the wick tube 6. A rocker member 10, mounted for rocking movement on the base 1 is provided with an upstanding forked arm 11, between the furcations of which engages and rides the offset crank portion 8' formed between one of the downturned end portions of the plate and the adjacent trunnion. The rocker member further has a pair of oppositely and downwardly extending arms 12, passing through and operating in slot 1' of the base. Supported beneath the base is an arcuate shape tube or casing 13, provided throughout a portion of its length with a pair of diametrically opposing slots 14 in which operates an actuating pin or member 15 for engagement with the rocker arms disposed in the path of travel of the pin. The pin is suitably mounted against displacement and actuated by the coiled spring 16, housed by the casing. The movement of the pin is governed by the plunger 17, connected for movement with the pin and operating in the closed portion 13' of the casing to compress the air in advance thereof. The escape of the cushioning air is permitted through an apertured cap 18, the retardation of the plunger being controlled by the size of the aperture in the cap. When in set position, the pin 15 engages in seats 13 in which position, the extinguisher is in an inoperative position.

In operation, the pin is unseated, from notch 13'' and, under the action of the coiled spring and the retarding influence of the plunger 17 in the cylinder 13', slowly travels its course and engages the rocker arm for moving the plate 8 over the wick tube. The slow travel of the pin may consume several minutes of time, in which instance it will be advisable to give a warning, within a shorter interval of time, when the light will be extinguished. At a predetermined point, I mount on the casing a signal bell 20 with a clapper 21, having a finger 22 projecting into the path of the downturned handle portion of the actuating pin. On swinging the cap 3 open, the extinguisher is disconnected from the rocker member and thereby the various working parts are easily accessible.

Having thus described my invention, what I claim as new, and desire to secure by Letters Patent of the United States of America, is:

1. A device of the character described

comprising a burner, means for extinguishing the flame thereof, spring actuated means for operating the first means, and pneumatic means controlling the movement 5 of the second means by its spring.

2. A device of the character described comprising a burner, means for extinguishing the flame thereof, spring actuated means for operating the first means, and cushioning 10 means controlling the movement of the second means by its spring.

3. A device of the character described comprising a burner, means for extinguishing the flame thereof, spring actuated means 15 for operating the first means, a compression cylinder, and a plunger operable in the cylinder for controlling the second means.

4. A device of the character described comprising a burner having a base and a 20 movably mounted cap, an extinguisher plate carried by the cap for movement and having a crank portion, and means pivoted on the base having an upwardly extending forked element receiving the crank portion of the 25 plate to form a releasable connection with the extinguisher plate for operating the latter and permitting of movement of the burner cap.

5. A device of the character described comprising a burner, means for extinguishing the flame thereof, rocker means pivoted 30 between its ends for operating the first means, and means for rocking the second means.

25 6. A device of the character described comprising a burner, means for extinguishing the flame thereof, rocker means for

operating the first means having spaced downwardly extending arms, and spring actuated means for engaging the arms rocking 40 the second means.

7. A device of the character described comprising a burner, means for extinguishing the flame thereof, and means for operating the extinguishing means comprising a 45 casing having a pneumatic chamber and a housing, an actuating member, spring means in the housing for moving the actuating member, and means in the chamber for controlling the movement of the actuating 50 member.

8. A device of the character described comprising a burner, means for extinguishing the flame thereof comprising a plate having oppositely extending trunnions for 55 swingingly mounting said plate, rocker means consisting of a furcated arm, forming an operative connection with the first means, and spaced rocker arms, and means engaging the rocker arms to move the first 60 means from and to an operative position.

9. A device of the character described comprising a burner, means for extinguishing the flame thereof, means normally free of and mounted for movement toward the 65 first means for operating the latter, and signal means operable by the second means prior to the act of extinguishment.

Signed at Seattle, Washington, this 16th day of December 1913.

EDDY M. KLINTBERG.
